United States Patent Office

Des. 181,119
Patented Oct. 8, 1957

181,119

REFRIGERATOR HANDLE

Harold S. Boutin, Curtice, Ohio, assignor to Revco Inc.,
Deerfield, Mich., a corporation of Michigan

Application May 13, 1957, Serial No. 46,127

Term of patent 14 years

(Cl. D67—3)

Figure 1 is a front elevation of a refrigerator handle showing my new design.

Figure 2 is a side elevation thereof.

Figure 3 is an end elevation thereof.

I claim:

The ornamental design for a refrigerator handle, as shown.
